Atty.

UNITED STATES PATENT OFFICE.

GEORGE A. McGARR, OF PHILADELPHIA, PENNSYLVANIA.

BROOM-BRIDLE.

1,401,342.

Specification of Letters Patent. Patented Dec. 27, 1921.

Application filed June 6, 1919. Serial No. 302,174.

To all whom it may concern:

Be it known that I, GEORGE A. McGARR, a citizen of the United States, residing at Philadelphia, in the county of Philadelphia and State of Pennsylvania, have invented 5 new and useful Improvements in Broom-Bridles, of which the following is a specification.

My invention relates to a new and useful 10 improvement in broom bridles, and has for its object to provide an exceedingly simple and effective device of this description, which may be readily attached to a broom during the course of the manufacture of the 15 same, or attached thereto after the broom is completed.

A further object of my invention is to so 20 bridle a broom that the straws thereof will have a limited movement under spring pressure 25 so as to avoid the fracturing or breaking of the straws at the point of contact of the bridle therewith; and

A still further object of my invention is to so construct and arrange the bridle and 25 the attaching element thereof that said bridle will have a limited swinging movement to adapt itself to the swaying of the straws of the broom when in use.

With these ends in view, this invention 30 consists in the details of construction and combination of elements hereinafter set forth, and then specifically designated by the claim.

In order that those skilled in the art to 35 which this invention appertains may understand how to make and use the same, I will describe its construction in detail, referring by numerals to the accompanying drawings forming a part of this application, in which:

40 Figure 1 is a side elevation of a broom, having a bridle made in accordance with my improvement applied thereto.

Fig. 2 is an enlarged plan view of the blank from which the attaching member of 45 the bridle is produced.

Fig. 3 is a section of a portion of the broom showing one form of my improved bridle attaching member secured on the broom.

50 Fig. 4 is a view similar to Fig. 2, showing a blank of slightly modified form, intended for producing an attaching member which may be readily secured to the broom after the same has been manufactured.

55 Fig. 5 is an edge elevation of the attaching

member made from the blank shown in Fig. 4.

Fig. 6 is a section of a portion of a broom showing the attaching member illustrated in Fig. 5 secured to the broom by forcing 60 the prongs thereof into the straw.

Fig. 7 is a detail view showing a portion of the bridle members engaged with the attaching member.

In carrying out my invention as here embodied, 1 represents an attaching member, which is made from a rectangular blank, with teeth formed along the two end edges thereof, as clearly illustrated in Fig. 2, this blank having an elongated hole 2. The 70 completed attaching member formed from this blank has the inset legs 3 and the outset teeth 4, that is to say the blank is so bent as to produce these legs from a portion thereof, the legs standing at an obtuse angle 75 from the body, and the teeth being bent outward from the legs at approximately right angles.

Two of the attaching members as thus described are embedded in the straws of the 80 broom during the process of manufacture of said broom, and therefore become a permanent part thereof.

My invention contemplates two bridle members, each consisting of the loop 5 85 adapted to surround a portion of the broom below the stitching 6 of said broom, and these bridle members have two arms 7 which extend upward on each side of the broom, terminating in the hooks 8 adapted to engage with the attaching members one on each side of the broom by passing through the elongated holes in said attaching members.

The arms 7 are so formed as to produce the 95 offset curve 9 in which the ends of the coil spring 10 rest, said ends being bent around said offset curve as clearly shown in Fig. 1.

The above described construction and arrangement gives the bridle a free swinging 100 movement within certain limitations to follow the movements of the broom straw when the broom is in use, but at all times maintains a spring pressure upon the straw so as to facilitate the sweeping operation of the 105 broom.

In practice the spring 10 on each side of the broom is so coiled and its length is such that it will be partly distended when the bridle is placed upon the broom, thus giv- 110

ing an initial pressure upon the straw, yet permitting a further distention of the spring during the sweeping operation.

In Figs. 4, 5 and 6, I have shown a slightly modified form of the attaching member in which the legs 11 are elongated and notched so as to form prongs, and these legs are bent out at right angles to the body of the attaching member approximately 10 upon the line of union of said legs and the body as shown in Fig. 5, and the pointed ends of said legs are set at a slightly inward angle so that when the attaching member is forced into the straw of the broom after the latter has been manufactured, the legs will be gradually bent inward until reaching the approximate position shown in Fig. 6 thereby firmly locking the attaching member firmly to the broom, the bridle being 20 connected to these attaching members in the same manner as above described.

While I have shown and described my invention as adapted for use upon brooms, it is obvious that it is also applicable to 25 brushes.

Of course I do not wish to be limited to the exact shape of the attaching member nor to the exact details of construction of the bridle member, as these may be varied with-

in the limits of the appended claim without departing from the spirit of my invention.

Having thus fully described my invention, what I claim as new and useful is:

In a device of the character described, 35 two attaching members each having a slot therein and carrying means for securement to a broom body, one of said members being located on each side of the broom body, two bridle sections spaced apart each consisting of a loop adapted to surround a portion of the broom body, and to straddle one edge thereof, two arms projecting from said loop and provided with offsets adjacent 40 said loop, hooks formed from the ends of 45 said arms for engagement with the slots in the attaching members whereby the bridle sections are pivoted to said attaching members, and springs attached to the offset portion of the bridle sections and lying within 50 the spaces between said bridle sections, one on each side of the broom body, for drawing the looped portions of said bridle sections toward each other.

In testimony whereof I have hereunto af- 55 fixed my signature.

GEORGE A. McGARR.
